DISPLAY STAND FOR MUSICAL INSTRUMENTS

James H. Lorenson, 946 S. 3rd, Salina, Kans.

Filed Mar. 14, 1960, Ser. No. 59,723

Term of patent 3½ years

(Cl. D80—10)

Fig. 1.

Fig. 2.

Fig. 4.

Fig. 3.

Fig. 1 is a perspective view of a display stand for musical instruments, showing my new design.

Fig. 2 is a top plan view thereof;

Fig. 3 is a front elevational view thereof; and

Fig. 4 is a side elevational view thereof.

I claim:

The ornamental design for a display stand for musical instruments, as shown.
